DIELECTRIC HEATING MEANS WITH AUTOMATIC COMPENSATION FOR CAPACITANCE VARIATION

Albert Schuman, Glendale, Calif., assignor to Westinghouse Electric Corporation, East Pittsburgh, Pa., a corporation of Pennsylvania

Application September 20, 1947, Serial No. 775,176

1 Claim. (Cl. 219—47)

1

My invention is generally related to the dielectric heat-treatment of materials, such as laminated plastics, resins, preforms, or the like, which undergo a change in dimensions during heat-treatment. More particularly, my invention is directed to improvements in apparatus for the treatment of such materials under heat and pressure, the heat being introduced dielectrically by means of spaced relatively insulated heating-electrodes on opposite sides of the material; the heating-electrodes preferably being pressed toward each other.

Dielectric heating generally requires high-frequency power in the order of 5-50 megacycles and more; and in order to get a satisfactory transfer of power from the generator or other source of high-frequency into the material between the relatively insulating heating-electrodes, it is desirable to have the heating-electrodes connected in or part of a branch circuit or network which is tuned to the frequency of the high-frequency power supply or which is impedance matched to a source of high-frequency power supply such as a high-frequency transmission line. However, during heat-treatment, the physical characteristics of a material may change, as for example, by a change in the thickness of the material between the heating-electrodes, as the material is being heat-treated. This is especially true of preforms or preliminary substances containing blowing agents. Such change affects the effective capacitance provided by the spaced heating-electrodes. The change in the capacitance may be great enough to seriously disturb the tuning or matching, and hence the amount of power delivered to the material.

An object of my invention is to provide a dielectric heating system of a type described in which changes in the capacitance between its spaced relatively insulating heating-electrodes because of changes in the thickness of material being heat-treated, are automatically compensated for, at least in part, by a combined mechanical and electrical mechanism which is directly responsive to the changing thickness of the material.

In general, in accordance with my invention, the heating-electrodes are part of a tuning or matching network which is provided with an auxiliary adjustable reactor, either an inductance coil or capacitor. This reactor is varied by a member which moves in response to changes in a dimension of the material being heat-treated. The member may be one of the heating-electrodes, or a distinct device. Movement of the

member changes the variable reactor preferably so as to keep the inductance and capacitance relations in the network at some predetermined value or values, although the capacitance between the heating-electrodes changes as the material undergoes a physical change in its size.

My invention is especially useful in connection with a dielectric heating system in which the material is heat-treated between two platens of a press. In such case, the member controlling the variation in the auxiliary reactor can be mechanically connected to a movable platen of the press, or can be placed on or in the material so that its position is changed when the size of the material changes.

An object of my invention is to provide a dielectric heating system of a type described, in which a variable dielectric load, consisting of the heating-electrodes and all of the material therebetween, automatically controls a reactor for maintaining the efficiency of the transfer of high-frequency power to the load.

Features, innovations, methods and combinations of my invention, in addition to the foregoing, will be discernible from the following description and generally schematic drawing of several embodiments of the invention.

In the drawing:

Figure 1 is a wiring diagram of an embodiment of my invention in which a heating-electrode is mechanically connected to a movable plate of a variable capacitor, the capacitor being electrically in series with the dielectric load;

Fig. 2 is a wiring diagram of a modified form of my invention as more particularly related to a press;

Fig. 3 is a view taken substantially along the line III—III of Fig. 2;

Fig. 4 is a wiring diagram of a further modified form of my invention in which the movement of a platen is amplified for controlling a capacitor in parallel with the dielectric load;

Figs. 5 and 6 are wiring diagrams of further modified forms of my invention in which the dielectric load changes a variable inductance coil, Fig. 5 showing the coil electrically in parallel with the load, and Fig. 6 showing the coil in series with the load; and

Fig. 7 is an abbreviated view of a still further form of my invention in which an air gap is provided in series with the material being heat-treated.

My invention can be conveniently described in connection with plastics of a type made from layers of paper, cloth or other substances which are

first impregnated with a resin and subsequently cured under heat and pressure; the heat being supplied dielectrically while the substance is in a press. Preforms for plastic molding are a further example of materials which usually undergo such changes. Preliminary to heat-treatment, the impregnated paper etc., is compressed between the platens of the press to as much as $\frac{1}{4}$ of its original size. The heating-electrodes in the press, which may comprise the platens themselves, and the material therebetween form a dielectric load. This dielectric load has the effect of a capacitor and is usually part of a tuned network or part of an impedance network, depending on whether the network is energized directly from a tube-oscillator generator, or through a high-frequency transmission line such as a coaxial cable. Usually the heat-treatment is accompanied by a change in the thickness and in the loss factor of the material. By loss factor is meant a combination of the power factor and dielectric constant of the material. Hence, the capacitance represented by the dielectric load alters materially as the material heats or cures, so that the relationship of the inductance, L, and capacitance, C, in the network of which the load is a part, is disturbed.

It is possible to continuously retune or rematch the L-C relations of a network by manual operation of a reactor connected to the dielectric load, but such a method has limited application because it may require an operator to stand near high-voltage high-frequency equipment. Experience has shown that the greatest change in the capacitance of the dielectric load and the largest change in the thickness of the material occur simultaneously during the first part of the heating period of a material such as resin-impregnated paper. The changes are very slow during the remainder of the heating period. The change in the thickness of the material can reflect itself as a change in the spacing between the press platens. In accordance with the teachings of my invention, the change in thickness controls an auxiliary adjustable reactor in the network of which the dielectric load is a part, for circuit tuning or matching.

Referring more particularly to the embodiment shown in Fig. 1, the dielectric heating load D consists of a pair of spaced relatively insulated heating-electrodes 2 and 4, having dielectric material or work 6 in the space therebetween.

Usually the heating-electrodes are metallic plates which are relatively movable. To obtain such an arrangement, one of the heating-electrodes may be fixed and the other movable. To illustrate the fixed heating-electrode in the drawing, slanted lines have been associated therewith on the side away from the material being treated.

In Fig. 1, the heating-electrode 2 is fixed and the other heating-electrode 4 is movable and rests on the material 6. Directly connected to the heating-electrode 4 is a movable bar member 8, which in turn is directly connected to a capacitor plate or plates 10 of a variable capacitor 12. The other capacitor plate or plates 14, which are insulated from the capacitor plate or plates 10, may be stationary.

The movable member 8 may be of metal so as to be a conductor of electricity. Hence, the member 8 essentially is a mechanical and electrical interconnection between a movable part or member of the heating-electrode 4 and the movable part 10 of the capacitor 12. However, a separate loose conductor 16 may be provided

between the heating-electrode 4 and the capacitor plate or plates 10 for the electrical current therebetween.

The dielectric load D and the capacitor 12 are connected in series to a secondary coil 18 which is coupled to an inductance coil 20 of a tank circuit 22 that is part of a tube-oscillator generator 24.

The network comprising the secondary coil 18, the capacitor 12, the dielectric load D, and the connections therebetween, can be adjusted in accordance with the frequency of the tube-oscillator generator 24 so that the desired voltage is present across the heating-electrodes 2 and 4. However, as the work 6 of the dielectric load D heats, its thickness and electrical properties change. A change in the thickness of the work raises the heating-electrode 4 which in turn lifts or moves the capacitor plate or plates 10 of the capacitor 12. The network can be kept in balance by so designing the capacitor 12 that its capacitance changes in an opposite sense to the change in the capacitance of the dielectric load D; that is, as the capacitance of the load decreases, the capacitance of the capacitor 12 increases.

In Fig. 1, the heating-electrode 2 has been shown grounded. This means that the heating-electrode 4, the movable member 8, and the capacitor 12 must be insulated from ground. If a connection 16 is used, it should also be insulated.

Fig. 2 shows an embodiment of my invention applied to a press, in sufficient detail to one skilled in the art. The press comprises bottom and top platens 30 and 32 respectively. The platen 30 is stationary, and the platen 32 is resiliently pressed toward the platen 30 by means of a pneumatically operated ram which is schematically represented at 34. Two layers of work 36a and 36b are provided in the space between the platens 30 and 32, the layers being separated by a third platen 38.

Electrically, the top and bottom platens 30 and 32 can be grounded and the intermediate platen 38 insulated so that, in effect, the surface of each platen, which faces another platen, provides a heating-electrode. The intermediate platen provides a bottom surface 40 facing the lower platen 30 and an upper surface 42 facing the top platen 32. The facing surfaces terminate the electric fields between the associated facing platens when high-frequency voltage is across the platen 38 on the one hand and the platens 30 and 32 on the other.

High-frequency power is derived from a tube-oscillator generator 44 having a tank circuit 54 to the inductance coil of which is coupled a coil or winding 56, one end of which is grounded as at 57. The other end of the coil 56 is connected by a conductor 58 to a stationary plate or plates 60 of a capacitor 62 having movable plate or plates 64 which are relatively insulated from the stationary capacitor plates 60. The movable capacitor plate or plates 64 are electrically connected to the insulated platen 38 through a flexible conductor 68. A rigid bar 70 is mechanically connected to the platen 38 and contacts a bar 72 through which the capacitor plate or plates 64 are moved.

When the work 36a and 36b between the platens absorbs energy, it changes in thickness, thereby raising the bar 70 because the ram 34 resiliently presses on the platen 32 with a constant pressure as is common in such presses. The bar 70 raises the bar 72, thus causing the capacitor plate or plates 64 to alter their overlap with the station-

ary capacitor plate or plates 60. The resulting change in capacitance will depend on the configuration of the peripheries of the respective plates. This is symbolically shown in Fig. 3 where the peripheries of the capacitor plates 60 and 64 are irregularly shaped in accordance with any desired mathematical formula so that a predetermined displacement of the platen 38 will cause a predetermined change in the capacitance of the capacitor 62.

Fig. 4 shows a further modified form of my invention in which the auxiliary reactor is electrically in parallel with the dielectric load D, and is operated by a grounded platen, in this case a top platen 74. The press of Fig. 4 is essentially the same as that shown in connection with Fig. 2; but in Fig. 4 the movable member 76, which corresponds to the bar 70 of Fig. 2, is attached to the top platen 74, and operates on a crank arm 78 that turns a shaft 80 in a speed-changing mechanism 82. The speed-changing mechanism 82 has a shaft 84 that turns a series of movable plates 86 with respect to a plurality of stationary plates 88 of a capacitor 90. By means of the speed-changing mechanism 82, a linear movement of the platen 74 is changed to a rotary movement of the capacitor plates 86. The speed-changing mechanism can move in direct proportion to that of the platen 74 or may include a cam arrangement for any desired motion change.

The particular network or networks and the connections to be used in them are known to the art, and do not form a part of my invention except insofar as a separate variable reactor is provided and is varied in accordance with a mechanical displacement of a member responding to a change in size or thickness of the material being heat-treated.

Instead of having a capacitor in series or in parallel with the dielectric heating load, as shown in Figs. 1-4, it is possible to use networks in which a variable inductance coil is arranged to be changed by displacement of a heating-electrode or platen. A variable inductance coil operable by a movable platen is indicated in Figs. 5 and 6; the coil being in parallel with the dielectric load in Fig. 5 and in series therewith in Fig. 6.

In Fig. 5, the grounded heating-electrode or platen 92 is movable while a fixed insulated electrode 93 is electrically connected to a manually variable inductance coil 94 which is electrically connected to an insulated conductor 96 of a high-frequency transmission line 98 having an outer grounded conductor 100. A variable inductance coil 102 is electrically in parallel with the dielectric load D, the electrical connection including a rigid metal bar member 104 movable with the grounded platen 92. The bar member 104 controls the position of a tap member 106 along the turns of the variable inductance coil 102.

In Fig. 6, a rigid insulating movable member 108 is rigidly mechanically connected to an insulated platen 110. The member 108 moves a movable tap 112 of a variable inductance coil 114 upwardly as the work 116 expands. A flexible conductor 117 electrically connects the tap 112 to the platen 110. The inductor 114 is electrically connected in series to a variable coil 118, which is electrically connected to the insulated conductor 120 of a coaxial transmission line 122. A manually variable capacitor 124 is electrically in parallel with dielectric load D for

completing the network from the insulated conductor 120.

It is obvious that the mechanical and electrical connections from a movable platen to the auxiliary variable reactor can be simply a simple metal bar, or the electrical and mechanical connections can be separated. Moreover, either the electrical or the mechanical connection, or both, can be accomplished by a part consisting of a plurality of independent members or a single part the portions of which can be considered as distinct members.

It is also obvious that the moving member which rests on the material or is otherwise responsive to the movement of the material, need not necessarily be a platen or a heating-electrode. This is indicated in Fig. 7 where two stationary relatively insulated heating-electrodes 130 and 132 are spaced to receive work 134 in the space therebetween; the work, however, not fully occupying the space so that an air gap 136 is provided between the top of the work and the upper heating-electrode 132. A movable member 138 rests on the material 134 so that it rises as the material heats. This movement of the movable member can control the reactance of a variable reactor in any suitable manner.

Since numerous changes may be made in the above-described constructions and electrical circuits, it is obvious that different embodiments of the invention may be made without departing from the spirit and scope thereof. It is intended that all matter contained in the foregoing description or shown in the accompanying drawings shall be interpreted as illustrative and not in a limiting sense, unless otherwise required by the prior art and claims.

I claim as my invention:

40 Dielectric heating means comprising, in combination, a pair of spaced relatively insulated heating-electrodes adapted to receive material therebetween of a type which changes its thickness between said heating-electrodes during heat-treatment, means comprising an electrical network for applying a high-frequency voltage across said heating-electrodes, whereby to provide an alternating electric field for heat-treating said material, one of said heating-electrodes being movable by the material as it changes in thickness, conductor means electrically grounding said movable heating-electrode, a mechanism constructed and arranged automatically to follow the movement of said movable heating-electrode, said network comprising a capacitor having a plurality of relatively insulated capacitor-plates, including a movable capacitor-plate, conductor means electrically grounding said movable capacitor-plate, said mechanism including an interconnection between said movable heating-electrode and said movable capacitor-plate, which moves said capacitor-plate in accordance with the movement of said movable heating-electrode.
